AUTOMATIC TARGET

Frank E. McAvoy, Teaneck, N. J., assignor to General Bronze Corporation, Long Island City, N. Y.

Application August 2, 1940, Serial No. 349,706

8 Claims. (Cl. 273—102)

This invention relates to improvements in target apparatus for shooting ranges and more particularly to apparatus for automatically and selectively controlling the movements of a member, such as a target, and the timing of the periods between movements.

In target practice, moving and bobbing targets are especially desirable for practicing and testing for alertness of marksmanship and for rapid firing. In this connection it is important that the timing of the target operation be accurate and that the appearing or bobbing characteristics thereof be easily and readily variable, both as to the interval of the target in "on" or firing position and the interval of the target in "off" or invisible position; it is also important that the bobbing of the target be continued for a particular number of cycles in the desired "on" and "off" timed relationship. It is also desirable to operate a plurality of bobbing targets either in synchronism or in a selective and unpredictable manner.

One of the objects of the invention, therefore, is to provide means for controlling the movement of a member, such as a target, capable of satisfying all of the above and other desired requirements.

Another object of the invention is to provide a novel timer control operable to alternatively effect energization and deenergization of a means for a predetermined number of cycles; and which is adjustable to vary the periods of energization and deenergization.

Still another object of the invention is to provide an improved operating means for the target capable of effecting the desired moving and bobbing characteristics.

A further object of the invention is to provide an automatic control for movable targets which is relatively simple and economical to install and operate.

The above and additional objects and features of the invention will become more apparent from the following detailed description when read in connection with the accompanying drawings, in which:

Figure 1 is a side view, partly in section, of a shooting range utilizing the invention;

Figure 2 is a side view of a target shown in 50 the firing or "on" position;

Figure 3 is a sectional view of a target operating means and a reversing relay associated therewith, and

Figure 4 is a wiring diagram of a timing means

for controlling the operation of a plurality of movable targets.

Figure 1 shows a shooting range having a shooting booth A and bench a. The target is shown generally at B. A back-stop C and sand pit D are arranged behind the target. At E the controlling mechanism is housed and the wiring in the conduit F leads to the target operating mechanism 14.

10 A plurality of movable targets may be located in a row at the rear of the range, and a plurality of booths A may be located adjacent each other at the other end of the range. Each shooter occupies a separate booth and shoots at a separate target. For convenience of illustration I shall describe five targets and five booths. The target 10 is shown in Figure 2 in a frontal or "on" position facing the shooter. The target 10 in Figure 1 is shown in an "off" position or with the edge of the target facing the shooter. Each target is provided with operating mechanism 14 which is located below the floor level in a pit above which a target supports 16 extends. The target 10 may be attached to the support 16 by a bracket and bolt assembly 18 or by other suitable means. The target operating mechanism rotates the target through 90° in moving it from "on" to "off" position. The target normally is in "off" position and is moved to "on" position so as to face the shooter. It is held in this position for a fixed interval, generally several seconds, after which it is again turned to "off" position. The shooter must fire while the target is facing him during the "on" interval. The target is then moved to and held in "off" position for another, usually longer, interval, and then is again moved to "on" position and held there for the fixed firing interval during which the shooter must fire the second shot. 25 The number of shots to be fired varies, usually from one to five, so that it is desirable that the target shall operate through a complete preselected cycle of from one to five times and then remain in "off" position. In addition, it is desirable to be able to pre-set the "on" interval and the "off" interval for different lengths of time or to change them during a single firing cycle.

30 It is also desirable that the target operating mechanism move the target from "on" to "off" position as rapidly as possible and to hold it fixed and steady in these positions. All of the above is accomplished in the manner to be described.

35 In Figure 3 of the drawings the target car-

rier 14 is shown to comprise a stationary member or stator 19 which includes two pairs of oppositely disposed poles 20 and 21, and 22 and 23 together with a centrally disposed armature or rotor 24 which is provided with two pairs of permanent magnets or poles 26 and 27, and 28 and 29. The target support 16 is attached to the rotor 24. The stator poles 20 and 21, and 22 and 23 are suitably wound so that when the current is flowing in one direction, the poles 20 and 21 will be north, and the poles 22 and 23 will be south. When the current is flowing in the other direction the poles will have the opposite polarity. The polarity of the armature poles 26 and 27 are south while the poles 28, 29 are north and this polarity is permanent. This arrangement of the stator and armature is such that when the windings are energized for a given polarity, the armature poles 26 to 29 will be attracted and repelled to positions adjacent stator poles of unlike polarity.

When energization of the windings of the stator poles 20 to 23 are reversed by changing the direction of the current, the armature 24 will be subjected to a substantial torque including both attracting and repelling forces capable of effecting a quick angular movement, thus moving the target supported thereby through an angle of 90°. In the arrangement of four armature and four stator poles, the combination of attracting and repelling forces provides a resulting torque which is eight times greater than the attracting or repelling force between two poles. If desired, a lesser or greater number than the four-pole arrangement illustrated may be provided.

It is obvious that the stator poles may be permanent magnets and the rotor poles changed in polarity by placing windings on them connected to the circuit through slip rings.

The rotor is normally biased off "dead center" by suitable means, such, for example, as by providing resilient stop means (not shown) to urge the armature poles 26, 27 and 28, 29 from a position diametrically opposite the stator poles 20 to 23. The armature being thus urged toward a position off "dead center," the armature will always be capable of immediate response to changes in stator polarity.

The target carrier relay 32 shown in Figure 2 operates to change the direction of the current in the stator windings and comprises a solenoid 33 controlled by the energization of the circuit E1. When the solenoid 33 is energized the switches 36 and 37 are actuated to reverse the connections of the line L₁ and L₂ with respect to the windings of the stator poles 20 to 23. Thus, upon energization of the relay 32 the polarity of the stator poles is reversed, and when the relay is deenergized the polarity is again reversed to that which it was prior to the energization of the relay. Each time the relay is energized, the target changes its position from an edgewise or "off" position to a frontal or "on" position and remains in "on" position as long as the relay is energized.

In Figure 4 of the drawings, I have shown a control circuit including a timer T₁ which controls the period during which a target is in "on" position and another timer T₂ which controls the period of time during which the target is in "off" position. A number of automatically operable relays to be hereinafter described respond to the timing operations of the timers T₁ and T₂ to control the energization and deenergization of the

relays 32. The number of cycles of coordinated operation of the timers T₁ and T₂ is controlled by the manual setting of a selector means MS.

The timers T₁ and T₂ are identical and of a well known automatic reset type, so that only one need be briefly described. Referring to the timer T₁, the movable contact 44 is normally maintained in engagement with contact 46 and caused to move therefrom and engage a second contact 47 at the termination of the timing period for which the timer is set. The movable contact 44 remains in engagement with the contact 47 until the timer is deenergized, whereupon the movable contact 44 reengages the contact 46. The timer is provided with a dial 48 and an index member that is set by hand to indicate and set the timing period. The timer is operated electrically by the circuits 73 and 76.

The timer T₂ is likewise provided with a movable contact 54 which is adapted to be moved from the normal position (illustrated) at the end of the timing period for which the timer is set to a position in engagement with the contact 51.

The manual selector means MS comprises a manually operable index 60 and a plurality of contacts 1 to 5; if desired a lesser or greater number of contacts may be provided. When the index 60 is positioned in engagement with one of the contacts 1 to 5, the number of timing cycles is thereby determined. For example, where the index 60 engages contact No. 2, the target will be actuated automatically by the control system so as to be moved from an "off" position to "on" position for the duration of the timing period of the timer T₁, then to an "off" position where it remains for the time set for the timer T₂; then again to an "on" position for the time period of timer T₁, and finally to the "off" position. Thus, the control effects two bobbing operations of the target, the control thereafter discontinuing the bobbing operation. Should the index be set at No. 5, it would produce 5 of the target bobbing operations, i. e., five separate operations in which the target faces the shooter.

The timing intervals for T₁ and T₂ may be changed during a cycle. For example, MS may be set for 5 bobbing operations, the "on" interval set for 3 seconds on timer T₁ and the "off" interval for 5 seconds. After three bobbing operations at these intervals the range master may move the timers so as to set T₁ for 5 seconds and T₂ for 15 seconds. The last two bobbing operations of the cycle will follow the latter set timing intervals.

The mechanism for control of this cycling operation comprises a plurality of contacts 1a to 5a connected with the corresponding contacts 1 to 5. A movable contact 62 is operatively associated with these contacts and moves one step for each bobbing operation until it reaches the corresponding contact representing the number of cycles for which the selector MS is set. The contact 62 is controlled by a ratchet 64, a pawl mechanism 65 and a reset spring 66. During timing operations the ratchet mechanism 65 is arranged for actuation by a stepping relay SR which is energized upon each energization of the timer T₁ as hereinafter described. A reset relay RR is provided to disengage the pawl mechanism 65 with respect to the ratchet 64, when the predetermined number of cycles have been completed, whereby the spring 66 is permitted to return the contact 62 to the initial position shown in Figure 4.

Wire E1 (Figure 4) leads to the relay 33 (Fig-

ure 3), and wires B₂ to B₅ lead to four other relays similar to 33 each of which controls a separate target actuating mechanism 14.

It will be seen therefore that in a range comprising five targets in a row at the rear end of the range and five booths at the front end of the range, there will be five target operating mechanisms 14, the first one being controlled by an impulse, through wire B₁, the second one being controlled by an impulse through B₂, etc.

There may be times when less than five men are shooting at the same time. For example, if men are shooting only from booths 1 and 2, only the first and second targets need be operated. In this event, the range master will close switches S₁ and S₂ and the impulses from the timing control which come through wire 83 will be sent only through wires B₁ and B₂. If five men are shooting all five switches S₁ to S₅ will be closed.

If desired the range master may alternate the operation of the targets by closing some of the switches during some of the cycles and then closing others. Also, he may interrupt the action of any of the targets part way in its cycle by opening the switch corresponding to that target. If manual control is desired, instead of automatic timing, this can be done by means of push buttons P₁ to P₅. If P₁ is pushed, a circuit from L₂, through P₁ B₁, relay 33 to L₁ is completed. It is apparent that as long as the contact P₁ is kept closed the first target will remain in "on" position and will return to "off" position.

All of the mechanism, switches and push-buttons shown in Figure 4 are located at E in Figure 1, and generally in the form of a panel on the range master's desk. It will be seen that by the controls described, the range master is enabled to operate any or all of the targets in any manner, manually or automatic.

The operation and coordination of the automatic timers, the selector means MS and the associated relays are described as follows:

To initiate a control operation, the timers T₁ and T₂ are set to indicate the periods of time during which the target or other movable means is to be maintained in "on" position and then in "off" position. For example, it may be desirable to set the timer T₁ to maintain a target in "on" position for one second and the timer T₂ set for maintaining the target in "off" position for three seconds. This timing relation, however, is given by way of example only since various timing relations may be had by different settings on the timers T₁ and T₂. The number of cycles is set by the controls MS, and the number of targets to be actuated are set by switches S₁ to S₅.

After the timers T₁ and T₂ have been set for the desired timing relation, the starting button SB is closed, thereby energizing the timer T₁ by energization of a relay R₁. The relay circuit can be traced from the line L₁ through wire 16, button SB, wire 11, relay R₁ and wire 72 to line L₂. The energization of relay R₁ actuates switches 74 and 75 from open to closed positions. The closing of the switch 74 provides a holding circuit for the relay R₁ from the line L₁ through switch 44, contact 46, switch 74, relay R₁ and wire 72. The closing of switch 75 completes a circuit energizing the timer T₁ through wire 73 and 76. The closing of the switch 75 also completes a second circuit from the line L₂ through switch 75, wires 17, 78, relay R₂ and wire 79 to the line L₁.

The energization of the relay R₂ actuates switches 80 and 82 from open to closed positions.

The closed switch 80 completes a circuit from line L₂ through the switch 80 and wire 83 to a bank of switches S₁ to S₅. Thus the target will turn to "on" position as soon as the circuit to wire 83 is completed.

The closing of switch 82 completes a circuit from line L₂ through switch 82, wire 84, stepping relay SR and wire 85 to the line L₁. The energization of the relay SR operates the pawl mechanism 65 to ratchet the contact 62 one step from initial position to engagement with the contact 1a. The movement of the contact 62 from initial position permits the switch 90 to close completing a holding circuit for the relay R₂. This circuit extends from line L₂ through wire 91, contacts 92, 93, wire 94, switch 90, wire 95, contacts 96, 97, wire 98, wire 78, relay R₂ and wire 79 to line L₁.

If the index 60 had been placed in engagement with contact No. 1, a circuit would have been completed by the engagement of movable contact 62 and contact No. 1a to deenergize the system upon the termination of the timing period of timer T₂.

Continuing the sequence of operation, the movable contact 44 will break engagement with the contact 46 upon the termination of the timing period for which the timer T₁ is set, and engage the contact 47. The disengagement of the contacts 44, 46 deenergizes relay R₁, permitting the switches 74 and 75 to return to open position. While the closing of the switch 75 effected energization of the timer T₁, the opening thereof does not deenergize the timer T₁, since the holding circuit of relay R₂ maintains the timer energized until the switch 92, 93 is opened.

The closing of the contacts 44, 47 completes a circuit from line L₁ through wire 100 and locking relay LR₂ to line L₂. The energization of relay LR₂ attracts the latch 102, thereby releasing the movable contact 92 which disengages the contact 93 and engages contact 104. The opening of the contacts 92, 93 opens the holding circuits to the timer T₁ and relay R₂, thereby deenergizing the timer T₁ and permitting the movable contact 44 to reengage contact 46 and the switches 80 and 82 to open. The opening of switch 80 opens the circuit to wire 83, thereby deenergizing relays 33 and moving the target to "off" position. The opening of switch 82 operates to deenergize the stepping relay SR, to prepare the ratcheting device for a new ratchet movement of the contact 62.

The closing of the contacts 92, 103 by the energization of relay LR₂ completes a circuit to energize the timer T₂. The operation of the timer T₂ controls the period during which power is cut off from the circuit 83.

At the termination of the timing period of timer T₂, the switch 54 is moved to closed position with the contact 57 to establish a circuit from line L₁ through wire 104, relay LR₁ and wire 105 to actuate the movable contact 92 to latched position. The closing of contacts 92, 93 establishes a circuit through wires 91, 94, switch 90, wire 95, contacts 96, 97, wires 97, 78, relay R₂ and wire 79 to line L₁ to reenergize the relay R₂. The closing of the contacts 92, 93 also establishes a circuit through the timer T₁ leading from the junction to wires 78, 98 through wires 77 and 16, timer T₁ and wire 73 to line L₁, whereby the timer T₁ is energized for a second "on" timing period. The actuation of the switches 80 and 82 by reenergization of relay R₂ provides for the energization of circuit 83 and also the energiza-

tion of the stepping relay SR to move the contact 62 another step forward to contact 2a.

The contact 62 has now engaged contact 2a and if it is assumed that MS is set for two cycles by connection of index 60 with contact No. 2, a stop circuit is prepared for energization upon the termination of the timing period of timer T₂. The timing period of timer T₁, however, is first completed ending the energization of the circuit 83 and energizing the relay LR₂ to effect reenergization of the timer T₂ as hereinbefore described. After the termination of the timing period of timer T₂ the switch 54 is moved into engagement with contact 57 completing a circuit energizing relay R₃. This circuit extends from the switch 54, 57 through wire 106, wire 107, relay R₃, wire 108, index 60, contacts 2 and 2a, movable contact 62 and wire 109 to line L₂. The energization of relay R₃ completes a holding circuit for the relay through wire 110, contacts 111, 116, wire 95, switch 90, contacts 92, 93 and wire 91 to line L₂. The closing of switch 112 by energization of relay R₃ completes the circuit of reset relay RR, the circuit being traced from line L₁ through wire 114, switch 112, wire 115, relay RR, wires 116, 108, index 60, contacts 2, 2a movable contact 62 and wire 109 to line L₂.

Immediately upon the energization of reset relay RR the pawl mechanism 65 is retracted to release the ratchet 64 whereupon the spring 66 resets the movable contact 62 to initial position, opening switch 90. The reset movement of the contact 62 immediately opens the circuits including the index 60. The relays R₃ and RR, however, are maintained energized by a holding circuit until the switch 90 is opened, which for relay R₃ includes from line L₁ the wire 114, switch 112, wire 120, relay R₃, wire 110, contacts 111, 116, wire 95, switch 90, wire 94, contacts 92, 93 and wire 91 to line L₁. The holding circuit for relay RR extends from line L₁ through wire 114, switch 112, wire 115, relay RR, wires 116, 110, contacts 111, 116, wire 95, switch 90, wire 94, contacts 92, 93 and wire 91 to line L₂.

It will therefore be apparent that the relays R₃ and RR are maintained energized until the movable contact 62 is completely reset to initial position where it opens switch 90 thereby deenergizing relays R₃ and RR. The reset operation and resulting opening of the switch 90 breaks the circuit which would normally effect the reenergization of the timer T₁ and the relay R₂. Thus the system is automatically deenergized after the completion of the number of cycles for which the index 60 of the selector means has been set. It can be reinitiated by the push button SB.

To summarize the operation of the control system, the actuation of the starting button SB operates the relay R₁ to effect energization of the timer T₁ to initiate the timing period and to energize through relay R₂ the circuit 83 to switches S₁ to S₅ and target circuits B₁ to B₅, the ratchet 64 at the same time being actuated one step forward. After the termination of the timing period for which the timer T₁ has been set, the contact 44 engages contact 47 energizing the relay LR₂. This causes the latch 102 to be tripped deenergizing the timer T₁, and to deenergize the relay R₂. The deenergization of the relay R₂ in turn deenergizes the circuit 83, while the tripping of the latch 102 in effecting the closing of contacts 92, 103 energizes the timer T₂ to initiate a timing period to determine the

period during which the target circuit is deenergized.

Upon the expiration of the timing period for which the timer T₂ has been set, relay LR₁ is energized to relatch the movable contact 92, deenergize the timer T₂ and reenergize the timer T₁ and the relay R₂. The energization of R₂ reenergizes the circuit 83 and moves the contact 62 one step forward. Thus the cycle has been completed and a second cycle initiated.

This sequence of cycles energizing the targets between "on" and "off" positions continues until electrical connections have been established between the index 60 and the movable contact 62. This connection completes a circuit which, upon termination of the next succeeding timing period of the timer T₂ and the closing of the contacts 54, 57, operates to energize the relay R₃ and the reset relay RR. These relays in turn effect the resetting of the movable contact 62 and deenergization of the control system.

From the foregoing description it will be readily apparent that many changes and variations in the invention are possible. For example, while only a bobbing form of target carrier is shown, many other target movements and movements or energizations of other devices can be controlled by my invention. A member, such as a target, may be moved up and down or given a lateral or to and fro movement or otherwise periodically energized, in accordance to the timing operating characteristics of my invention. It is to be understood, therefore, that the forms illustrated and described are to be regarded as illustrative of the invention only and not as limited to the following claims.

I claim:

1. A target, an actuating means therefor comprising motivatable means for supporting said target for movement between "on" and "off" positions, a device for moving said target from one of said positions to another upon energization and deenergization thereof, timing means for controlling the period of energization of said device, and a second timing means for controlling the period of deenergization of said device.

2. A target, an actuating means therefor comprising motivatable means for supporting said target for movement between "on" and "off" positions, a device for moving said target from one of said positions to another upon energization and deenergization thereof, timing means for controlling the period of energization of said device, a second timing means for controlling the period of deenergization of said device, and means for coordinating said timing means for successively energizing and deenergizing said device.

3. A target, an actuating means therefor comprising motivatable means for supporting said target for movement between "on" and "off" positions, a device for moving said target from one of said positions to another upon energization and deenergization thereof, a timer for controlling the periods of energization, a second timer for controlling the periods of deenergization, means responsive to the lapse of time for which the first mentioned timer has been set to deenergize said device and initiate operation of said second timer, and means responsive to the lapse of time for which said second timer has been set to reenergize said device and initiate operation of said first mentioned timer for new timing period.

4. A target, an actuating means therefor comprising motivatable means for supporting said

target for movement between "on" and "off" positions, a device for moving said target from one of said positions to another upon energization and deenergization thereof, a timer for controlling the periods of energization, a second timer for controlling the periods of deenergization, pre-settable registering means operable to stop operation of said device upon completion of a predetermined number of cycles of operation, means operable to coordinate the timers for successively energizing and deenergizing said device, and to actuate said registering means once for each cycle of operation.

5. A target, an actuating means therefor comprising and deenergizing operation when the said target for movement between "on" and "off" positions, a device for moving said target from one of said positions to another upon energization and deenergization thereof, timing means for controlling the periods of energization and deenergization of said device, means settable for a predetermined number of cycles of energization and deenergization, and means associated with said settable means for stopping the energizing and deenergizing operation when the said predetermined number of cycles have been effected.

6. A target, an actuating means therefor comprising motivatable means for supporting said target for movement between "on" and "off" positions, a device for moving said target from one of said positions to another upon energization and deenergization thereof, timing means for controlling the periods of energization and deenergization of said device, means for registering each cycle of energization and deenergization, reset means for said registering means, and means operable upon completion of a desired number of cycles to effect operation of said reset means.

7. Target apparatus comprising a plurality of target motivatable means each movable between "on" and "off" positions and including a magnetic rotor and stator, control means alternately energizable and deenergizable to change the magnetism of each stator, a timer for controlling the periods of energization, a second timer for controlling the periods of deenergization, means including cooperating relays for coordinating the timers for successively energizing and deenergizing said control means, means settable for a predetermined number of cycles of energization and deenergization, means for registering each cycle, reset means for said registering means, means operable upon completion of the predetermined number of cycles for stopping operation of said motivatable means and for effecting operation of said reset means, and a master control for determining which of the motivatable means are to be operated.

8. A target, an actuating means therefor comprising motivatable means for supporting said target for movement between "on" and "off" positions, a device for moving said target from one of said positions to another upon energization and deenergization thereof, a timer for controlling the periods of energization, a second timer for controlling the periods of deenergization, means including cooperating relays for coordinating the timers for successively energizing and deenergizing said device, means settable for a predetermined number of cycles of energization and deenergization, means for registering each cycle, reset means for said registering means, and means operable upon completion of the predetermined number of cycles for stopping operation of the apparatus and for effecting operation of said reset means.

FRANK E. McAVOY.

CERTIFICATE OF CORRECTION.

Patent No. 2,307,147.

January 5, 1943.

FRANK E. McAVOY.

It is hereby certified that error appears in the printed specification of the above numbered patent requiring correction as follows: Page 1, second column, line 23, for "supports" read --support--; page 3, first column, line 12, for "example" read --example--; line 55, for "controls" read --control--; page 5, first column, line 15, claim 5, for "gizing and de-energizing operation when the said" read --prising motivatable means for supporting said--; and that the said Letters Patent should be read with this correction therein that the same may conform to the record of the case in the Patent Office.

Signed and sealed this 9th day of February, A. D. 1943.

Henry Van Arsdale,
Acting Commissioner of Patents.
